ATTORNEY.

UNITED STATES PATENT OFFICE.

JOSEPH M. COUGHLAN, OF ST. JOSEPH, MISSOURI.

SHADE AND CURTAIN RACK.

No. 925,996.

Specification of Letters Patent. Patented June 22, 1909.

Application filed February 21, 1908. Serial No. 417,048.

To all whom it may concern:

Be it known that I, JOSEPH M. COUGHLAN, a citizen of the United States, residing at St. Joseph, in the county of Buchanan and State of Missouri, have invented certain new and useful Improvements in a Shade and Curtain Rack; and I do declare the following to be a full, clear, and exact description of the invention such as will enable others skilled in the art to which it appertains to make and use the same, reference being had to the accompanying drawings, and to the letters of reference marked thereon, which form a part of this specification.

15 The object sought by me is to provide an adjustable device especially adapted to support curtains and shades at windows; that can be placed and held in position without the use of nails or screws, thus obviating the defacement of or injury to the woodwork; that can be instantly adjusted to the width of any window; that will support a shade or curtains, or both, simultaneously, and that will permit the removal of the shade and curtains from one window to another without removing the shade, pole and curtains from the device.

20 I attain my object by the mechanism illustrated in the accompanying drawings in which:

Figure 1 is a front elevation of the rack, the dotted lines, broken away, indicating the position in which the curtain pole and shade are carried; Fig. 2 is a top view of the rack, a 25 curtain pole shown by dotted lines, broken away; Fig. 3 is an end elevation showing the manner in which the rack is attached to a window casing; Fig. 4 is an end view of a bracket and eyelet therein; Fig. 5 is an enlarged detail of duplicate adjustable straps with clamp and sleeve thereon; Fig. 6 is a perspective of the lock band of the clamping device showing the top and bottom flanges thereof with perforations therein; Fig. 7 is a 40 perspective of the clamp and the axles thereon, and Fig. 8 is a perspective of the bifurcated tips of one of the supporting bands that engage with the upper edge of the top cross piece of the casing of a window.

45 Similar letters refer to similar parts in the several views.

All the parts of the device are constructed, preferably, of metal.

50 A A are duplicate straps which fit close

against each other when the device is adjusted to its narrowest compass as shown in Fig. 1; when widened to adjust to windows and casements of greater width, their outer ends separate as shown in Fig. 5. Said outer ends are bent at a right angle forward 55 forming a shade bracket B provided with a countersunk eyelet b to receive the cap pin at one end of the shade, the outer end of the other strap forming a bracket C provided with a countersunk slot c to receive the cap 60 pin at the opposite end of the shade.

D D are supporting bands the bottom ends of which are attached rigidly on the face of each strap in the angle formed by the forward projection of the bracket. The top 65 ends D' D' of said supporting bands are turned at a right angle backward adapting them to rest upon the upper edge of the horizontal top cross piece of the window casing or upon the blocks usually forming the 70 corner pieces of such frames. The tips d d of these top ends of the bands are bifurcated as shown in Fig. 8 so that with slight pressure or a light tap they may be driven between the grains of the wood thus holding the device securely in position until pressed upward out of connection with said cross piece. Curved rests E E to carry a curtain pole are rigidly attached on the face of each supporting band.

75 A sleeve H is rigidly attached on the inner end of one of adjustable straps A A. This sleeve is of sufficient width to permit the other strap to pass freely back and forth through it. A lock band J is rigidly attached on the face of said other adjustable strap at its end, its top and bottom ends K K flanged at a right angle rearward. Oppositely in each of said flanges K K there is a 80 perforation L L. A thumb clamp M, as shown 85 in Fig. 7, has axles O O integral therewith, which are adapted to engage with perforations L L. Practically at a right angle with the body of said thumb clamp and integral therewith, there is an extension P. When 90 the body of this thumb clamp is in the position shown in Fig. 5, this extension binds straps A A immovably together; when said thumb clamp is in the position shown by dotted lines in Fig. 5 the straps are released 95 and the rack may be widened or narrowed, thus adjusting it to any window or other place where it may be suitable for use. Dot-

ted lines R indicate a curtain pole; dotted lines S indicate a shade, and T the top cross piece of a window frame.

What I claim and desire to secure by Letters Patent, is:—

1. In an adjustable combination shade and curtain rack, duplicate straps adapted to travel in contact beside each other, a sleeve rigid on the inner end of one of said straps the other strap being adapted to travel through the same, a lock band rigid on the face of the end of the opposite strap provided with a flanged top and bottom thereof each having perforations therein, a thumb clamp having a turned extension thereon, and axles integral therewith engaging with said perforations, said lock band and thumb screw serving as a sleeve for the travel of the opposite strap, forwardly bent brackets integral with the ends of said straps respectively provided with a countersunk slot and eyelet, the supporting bands rigidly attached to the face of said straps, the top ends thereof bent rearward and downward at right angles and provided with bifurcated tips adapted

to engage with a casing and the rests on the face of the supporting bands to carry a curtain pole, substantially as set forth and shown.

2. In an adjustable shade and curtain rack the combination of duplicate vertical supports provided with rests the top ends thereof bent at a right angle rearward, and having downwardly projected bifurcated tips, duplicate slidable straps respectively rigidly attached to said supports and the brackets integral with the outer ends thereof, a sleeve rigid on the inner end of one of said straps, a lock band rigid on the inner end of the other of said straps and a thumb clamp, said lock band and clamp serving both as a sleeve and lock for retaining the rack at any width to which adjusted, substantially as shown and described.

In testimony whereof, I affix my signature in the presence of two witnesses.

JOSEPH M. COUGHLAN.
